UNITED STATES PATENT OFFICE

ROBERT V. FESSLER, OF INDIANAPOLIS, INDIANA

DESIGN FOR A LAMP

Application filed November 20, 1929. Serial No. 33,508. Term of patent 7 years.

To all whom it may concern:

Be it known, that I, ROBERT V. FESSLER, a citizen of the United States, residing at Indianapolis, in the county of Marion and State of Indiana, have invented a new, original, and ornamental Design for a Lamp, of which the following is a specification:

The figure is a front elevation partially in perspective of a lamp showing my new design.

I claim:

The ornamental design for a lamp as shown.

In witness whereof, I, ROBERT V. FESSLER, have hereunto set my hand at Indianapolis, Indiana, this 18th day of November, A. D. one thousand nine hundred and twenty nine.

ROBERT V. FESSLER.
